FERRULE EXPANDING TOOL

George M. Graham, Detroit, Mich., assignor to
Hinckley-Myers Company, Jackson, Mich., a
corporation of Michigan

Application January 19, 1938, Serial No. 185,658

3 Claims. (CL 153—86)

This invention relates to tools for expanding articles into fixed positions in structures and more particularly to a tool for expanding metal ferrules into locking engagement with the surrounding structure of holes into which they have been inserted.

An important object of this invention is to provide a tool of novel design for expanding metal ferrules into fixed position in structures, such as into engagement with the surrounding portions of holes into which the ferrules are seated. This invention finds particular use in installing metal ferrules in the door handle apertures in the door panels of motor vehicles. For such use, the tool is light, compact and rugged for continuous rough usage on motor vehicle assembly lines. The elements comprising the tool are simple in formation and are easily and economically manufactured and assembled.

Various other objects, advantages and meritorious features of the invention will appear more fully from the following specification, appended claims and accompanying drawing, wherein:

Figure 1 is a longitudinal cross-sectional view of the tool showing the parts in initial operation condition.

Fig. 2 is a cross-sectional view of the ferrule expanding end of the tool showing a metal ferrule therein preparatory to inserting the same in a washer.

Fig. 3 is a cross-sectional view through an aperture in a metal panel showing a rubber washer in place about which the metal ferrule is crimped.

Fig. 4 is an elevation of my ferrule expanding tool broken away at each end to show its construction and functioning and showing the same in use.

Fig. 5 is a cross-sectional view taken through the construction shown in Fig. 1 transversely through the body portion 10 and nut 14.

Fig. 6 is a detail view of the slotted sleeve partially broken away to show the jaw sections thereof, and

Fig. 7 is an end view of the expandible sleeve showing the jaw sections thereof formed by the longitudinal slits cut therein.

Referring to the drawing in detail, the primary supporting part of the tool is formed by an elongated or tubular member 10. The exterior surface of this body is preferably knurled to facilitate handling of the tool during the operation of the tool. Extending axially through the body 10 in spaced relationship to the inner wall thereof is a rod 12. The opposite ends of this rod project beyond the ends of the tubular body 10. An

element or nut 14 preferably of hexangular shape as shown in Fig. 5 is slidably fitted in a corresponding shaped wall section 16 of the body 10. The element 14 is fixed to the rod 12 and slidably supports the same upon the axis of the body 10 in spaced relation to the inner walls thereof. The angular engagement of this element with the inner wall section 16 of the body 10 slidably keys the rod to the body so that the rod is only capable of a lengthwise movement.

The end section 18 of the rod adjacent the element 14 is externally threaded as shown. A nut 20 is threaded to this section and carries oppositely disposed arms forming a crank handle 22 for the tool. When the handle is rotated in one direction, such as in the direction of the arrow in Figs. 1 and 4, the inner edge of the nut 20 bears against the end of the body 10 and as a consequence the result of the threaded engagement of the nut 20 on the rod 12 the latter is caused to be moved longitudinally toward the right in Figs. 1 and 2. This longitudinal movement, unless otherwise restricted by the expansive action on a ferrule described later, is limited by the abutment of the hexangular nut 14 against shoulder 15 of the body 10.

The opposite projecting end of the rod 12 is gradually enlarged in diameter to form the active means for expanding the ferrule. This enlargement is preferably accomplished by threading a cone-shaped element 23 upon the end of the rod 12 with the cone increasing to a greater diameter as the outer end of the rod is approached. The maximum diameter of the cone 23 is less than the inner diameter of the type of ferrule to be expanded so that the latter may be slipped over the enlarged end of the rod.

Carried upon the end of the body 10 adjacent the enlarged end of the rod 12 is a circular member or cap 24. This member is capable of adjustment longitudinally of the body by reason of its threaded engagement to the end of the body as shown. A lock jaw nut 26 is also threaded on the body to lock the cap in any adjusted position. Other locking means, however, may be provided such as a lock screw extending radially through the member into engagement with the body. Member 24 is of a size substantially equal to the type of ferrule to be expanded. Its outer end is preferably beveled or chamfered at 28 to form an annular seat against which the flanged end of a ferrule 30 may be seated as shown in Fig. 2.

The enlarged cone-shaped end of the rod 12 acts on flexible means which upon radial expansion is capable of engaging the underside of a

ferrule and expanding the same into fixed position. In the present embodiment of the invention this means comprises a sleeve 32 threadedly secured at its inner end to an internal section 34 of the tool body. The opposite end of the sleeve projects beyond the threaded seating member 24 but short of the end of the rod 12. The sleeve is composed of flexible metal material having an inherent resiliency so that upon release from pressure of distortion it tends to return to its normal shape. The sleeve, or at least the projecting end thereof, is normally of a diameter less than the inner diameter of the type of ferrule upon which this tool is to be used. This enables a ferrule 38 to be slipped thereover as shown in Fig. 1.

The projecting end of the sleeve is provided with an annular projection or bead 36 having an inner inclined face 38. The sleeve is slitted lengthwise at equidistant points around its circumference as shown in Fig. 6 dividing the sleeve into a plurality of expandable sections or jaws. The slits extend a substantial distance along the sleeve and terminate adjacent the threaded end thereof as shown in Fig. 6. To prevent the sleeve from turning, a set screw 46 may be provided in the body 16 to lock the sleeve at its point of securing.

The tubular body has internal diameters of varying degrees to facilitate assembly. The hexagonal section 16 in which the nut 14 is slidably disposed is the smallest in diameter. The threaded section 34 is next in diameter size. The section 42 adjacent the cap end of the body is largest in diameter and circular in formation. This last section is greater in diameter than the inner end of sleeve 32 and the nut 14 so that these two elements may be inserted through the tubular body from left to right in Fig. 1 when the tool is assembled.

The tool described hereinabove is particularly adapted for expanding a door handle ferrule in place on a motor vehicle. The door handle projects through the door panel from one side to the other and the ferrule forms a support for the handle as well as to improve its appearance. A ferrule encircles the door handle at the point which it enters the door panel. In Fig. 3 a cross-sectional view through a door panel 44 is shown prior to the insertion of a ferrule. The aperture in the door panel preferably contains a flexible washer 46 composed preferably of rubber or some similar material.

To operate the tool the ferrule may be inserted into the door handle aperture of the washer and the operating end of the tool inserted therethrough or if desired the washer may be slipped upon the tool as shown in Fig. 2. In either event the jaws of the sleeve should be in their normal collapsed state to facilitate insertion of the jaws through the ferrule. The cap member 24 should be adjusted on the body until it engages the washer 38 as shown in Fig. 2. The handle is then rotated to draw the cone 23 into the end of the slit sleeve 32 expanding the sleeve jaws as shown in Fig. 4 against the ferrule 38 compressing the ferrule about the washer 46 into the shape shown.

What I claim:

1. A ferrule expanding tool comprising, in combination, a tubular body, a sleeve fixed at one end within the body against rotation and extending away from said fixed end axially through the body spaced therefrom and having its opposite end projecting beyond the end of the body and provided therebeyond with an outwardly project-

ing ferrule seating face bevelled on the side facing the end of the body, said sleeve being slitted lengthwise toward said opposite fixed end, a cap having an annular ferrule seating outer end face threaded upon the end of the body to project therebeyond toward the ferrule seating face on the end of the sleeve but spaced therefrom, said cap being threadedly adjustable lengthwise upon the body toward and away from the ferrule seating face of the sleeve, a rod extending axially through the sleeve and body projecting beyond the ends thereof and supported within the body against rotation but slidably lengthwise therethrough, that end of the rod which projects beyond the split end of the sleeve being tapered and of a diameter greater than the internal diameter of the split end of the sleeve to expand such split end of the sleeve as the rod is drawn thereinto, and means threaded upon the opposite end of the rod engaging the end of the body and operable upon rotation to move the rod lengthwise of the body.

2. A ferrule expanding tool comprising, in combination, a tubular body, a sleeve fixed at one end within the body against rotation and extending away from said fixed end axially through the body spaced therefrom and having its opposite end projecting beyond the end of the body and provided therebeyond with an outwardly projecting ferrule seating face bevelled on the side facing the end of the body, said sleeve being slitted lengthwise toward said opposite fixed end, a cap having an annular ferrule seating outer end face threaded upon the end of the body to project therebeyond toward the ferrule seating face on the end of the sleeve but spaced therefrom, said cap being threadedly adjustable lengthwise upon the body toward and away from the ferrule seating face of the sleeve, a rod extending axially through the sleeve and body projecting beyond the ends thereof, means supporting the rod within the body against rotation but for slidable movement lengthwise thereto, that end of the rod projecting beyond the split end of the sleeve being tapered and of a diameter greater than the internal diameter of the split end of the sleeve to expand the split end of the sleeve as the tapered end of the rod is drawn thereinto, means coupled with the opposite end of the rod to move the rod lengthwise through the body, and means limiting the movement of the rod through the body in the direction which expands the split end of the sleeve thereby limiting the expansion imparted to the sleeve by the rod.

3. A ferrule expanding tool comprising, in combination, a tubular body, a sleeve fixed at one end within the body against rotation and extending away from said fixed end axially through the body spaced therefrom and having its opposite end projecting beyond the end of the body and provided therebeyond with an outwardly projecting ferrule seating face bevelled on the side facing the end of the body, said sleeve being slitted lengthwise toward said opposite fixed end, a cap having an annular ferrule seating outer end face threaded upon the end of the body to project therebeyond toward the ferrule seating face on the end of the sleeve but spaced therefrom, said cap being threadedly adjustable lengthwise upon the body toward and away from the ferrule seating face of the sleeve, a rod extending axially through the sleeve and body projecting beyond the ends thereof, said rod having a nut fixed thereon, which nut is mounted within the body between the fixed end of the sleeve and the end

- of the body remote from the sleeve, said nut being slidable lengthwise through the body between the fixed end of the sleeve and the end of the body remote from the sleeve but held against rotation thereby, that end of the rod which projects beyond the end of the split sleeve being provided therebeyond with a tapered cone having a maximum diameter greater than the internal diameter of the split end of the sleeve to expand such split end of the sleeve as the cone is drawn thereinto, said body having a part adapted to engage said nut on the rod to limit the slideable movement of the rod in the direction to expand the split end of the sleeve. 5

GEORGE M. GRAHAM.
